AMMUNITION STRUCTURE AND LAUNCHING
DEVICE THEREFOR

Samuel Herbert Clarke, Baltimore, Md.

Application July 10, 1942, Serial No. 450,486

14 Claims.

(Cl. 89—1.5)

1

This invention relates to a novel form of ammunition structure and launching device therefor, and more specifically, it relates to an improved form of explosion-device; to at least two of such explosion-devices united with and by at least two flexible connectors to form a unitary structure that can be flexed and collapsed by either winding them on a spool-like explosion device, or by forming them into series of loops or bends; and to different forms of launching devices designed to launch the explosion devices substantially horizontally and with their lengths disposed transversely of the path of movement of the aircraft in which these devices are designed to be carried.

One object of this invention is to provide an ammunition structure that includes flexible connectors of such length that it is possible for its explosive end-portions to be in the water on opposite sides of a large ship while its intermediate parts are spaced apart for straddling up-standing or out-standing objects on or of the ship; so that instead of the ammunition structure sliding off and away from the ship, it will remain engaged with the ship while the force of gravitation and the relative motion of the water and ship effect the movement of one or both explosion-devices to position against the lateral sides or bottom of the ship where they will be exploded by appropriate time-controlled explosion-producing devices with which they are equipped.

A further object of this invention is to provide a series of rigid struts, each strut having its ends or end-portions united with the respective flexible connectors for the dual purpose of providing or preserving wide spaces between the flexible connectors so they can receive large objects therebetween, such as funnels, ventilating tubes, davits, etc., and of providing abutments that cooperate with the ship-carried objects to limit sliding movement to the minimum.

Another object of this invention is to provide simple and exceedingly practical means of quickly securing the struts to the flexible connectors which may be either chains, cables or parallel series of wires, etc., so the operations of mass-production are facilitated to the maximum.

Another object of the invention is to provide such unitary long ammunition, viz., wherein the flexible connectors of the explosion devices may be more than 100 feet, that can be wound or looped or otherwise reduced to a small fraction of the fully extended length, so it can be carried in a relatively short launching device within an airplane or blimp-carriage; also to

provide each such unitary ammunition structure and launching device with mutually cooperating means for assuring proper launching, viz., launching the ammunition device in its fully extended relation and with the relatively long connectors, explosion devices and rigid struts all substantially or approximately horizontal; so not only is the chance of hitting the target maximized by the exceedingly great length of the missile or ammunition structure, when substantially level or horizontal, but also is the chance of upstanding objects on or of the target passing between the flexible connectors maximized when the explosion devices and struts are substantially horizontal.

Another object is to provide different forms of explosion devices and different forms of launching devices for cooperative use in different sizes and kinds of aircraft and for use against ships and other targets of different sizes and kinds; for instance, a much longer ammunition structure would be effective on a large battle-ship or aircraft carrier than on a light cruiser or other relatively small ship, for on a small ship, a very long ammunition device of this kind would probably trail its explosion devices behind the ship instead of against the sides of the ship; whereas, a short ammunition structure when hitting a very broad-beamed ship, would probably deposit both explosion devices on deck where they would not be as effective as if exploded below, at or near the water-line of the ship's sides, or possibly at its bottom.

Other objects and important features are pointed out or implied in the following details of description, in connection with the accompanying drawings in which:

Fig. 1 is a top plan view of a very simple form of the unitary structure or device that comprises at least two explosion devices of spool-like construction on one or both of which can be wound the cables, or a part of the cables that here constitute the flexible connectors whose ends are either permanently or detachably secured to peripheral flanges of the explosion devices.

Fig. 2 is a front-to-rear vertical sectional view of a form of launching device especially designed for launching the spool-like explosion-devices and the adjuncts shown in Fig. 1, with or without additional adjuncts; the sectional parts between the upper and lower ones, being taken near the right side, the tapered right end of the drawing showing the rear or discharge end of the launching device; the broken-line circles being merely to indicate the peripheral positions of the bodies

and flanges of the explosion-devices whose tubular end-projections are seen in cross section.

Fig. 2A is a transverse vertical sectional view of a part of the structure at line 2A—2A of Fig. 2.

Fig. 2B is a transverse vertical sectional view of a part of the structure at line 2B—2B of Fig. 2.

Fig. 2C is a fragmental detail of a simple and effective form of rigid strut having its ends clamped over and welded to flexible connectors of which are shown fragments composed of parallel wires, preferably of spring steel.

Fig. 2D is an edge view of one of the rigid struts such as shown in Fig. 2C, only the ends of the wires being indicated in the end-loops.

Fig. 2E is an edge-view of one of the struts such as in Fig. 2D, except not completed by the closing of the end-loops and welding thereof.

Fig. 2F shows a modification of one end portion of a strut having its extreme end in an apertured guide-block, and a chain secured thereto and comprising one of the flexible connectors, in lieu of the cables and parallel wires shown in Figs. 1 and 2C.

Fig. 2G is an edge-view of the strut-fragment and a sectional view of the block and chain shown in Fig. 2F, taken along the line 2G—2G of Fig. 2F.

Fig. 3 is mainly a left-side view of a modified form of the ammunition-structure in a modified form of launching device designed especially for cooperation, where the flexible connectors may be over 100 feet, or even over 150 feet or more, and where the explosion-devices are so long and heavy that carriages are provided as accessories for properly supporting the explosion devices and for properly launching the latter; the rear end of this view being in vertical section; both the Figs. 2 and 3 showing fuselage-floors in section under the launching devices. Fig. 4 is a transverse vertical sectional view showing the lower-front and intermediate portions of a cage similar to that of Figs. 3 and 8, but slightly different, and containing a simple form of skidding carriage releasably secured therein in the proper position to support the foremost one of the explosion devices and to slide or skid rearward therewith when released and pulled as explained later herein.

Fig. 5 is a plan view showing a modified form of the ammunition structure shown in Fig. 1.

Fig. 6 is a plan view showing the device of Fig. 5 collapsed, and the explosion devices seated on carriages similar to that shown in either Fig. 4, 8 or other appropriate form, the parts of flexible connectors between the struts being looped or bent inward, to approximately parallel relation to the rigid struts, to points on opposite sides of the median line of the structure, as when they are on a floor of a launching device that is provided with means to restrain these loops against considerable movement and to release them for proper movement at the proper time, at will of the attendant or user.

Fig. 7 is a perspective view of a launching cage that constitutes the main part of the launching device or combination shown in Fig. 3, the holes showing where other parts of the launching device are to be secured in their respective places.

Fig. 8 is a transverse vertical sectional view taken substantially along the lines 8—8, 8—8 of Figs. 6 and 7; the front explosion device, on its carriage, being seated on the floor of the cage of the launching device such as in Fig. 3.

Fig. 9 is a rear view of the cage having some of its adjuncts in place, and some of them omitted, a part of the floor being broken away and in sec-

tion along the lines 9—9, 9—9 of Fig. 10, and the lower-rear part of the down-deflecting hood or guide being broken away.

Fig. 10 is a horizontal sectional view taken along the line 10—10 of Fig. 9, and parts of the ammunition structure being shown in normal position and partly in section on line 10—10.

Fig. 9A is a fragmental detail of a restraining device of which elements are shown in Figs. 10 and 11.

Fig. 11 is a top plan view of the form of carriage shown in Figs. 8 and 12.

Fig. 12 is a sectional view along the line 12—12 of Fig. 11, a section of cage-floor being added, 15 and the position of the supported explosion device being indicated in broken lines.

Fig. 13 is an end elevation of one of the explosion devices such as the one included in Fig. 8, having one of the guiding and spacing blocks in 20 the foreground.

Fig. 14 is an enlarged fragmental sectional view, partly in top-plan, illustrating a practical and effective means to prepare the time-controlled explosion producer for beginning its time-controlling operation, with its cooperating adjuncts.

Fig. 15 is an exploded top-plan view of the elements shown in Fig. 14, except the restraining key and end-guiding track.

Fig. 16 is a vertical front-to-rear sectional view 30 of the rear end-portion of the launching device shown fully in Fig. 3, the movable abutments or hinged restraining elements being shown in their ineffective or down positions.

Fig. 17 is an elevation of one of the complementary blocks shown in Figs. 14 and 15, but disposed at a different angle of view.

Fig. 18 is a fragmental detail view illustrating several modified elements including a spring key that cooperates in securing links of a flexible connector to an end-portion of one of the struts that is of tubular construction (see Sheet 2).

Fig. 19 is a sectional view taken along the line 19—20, of Fig. 18, viewed in direction of the upper arrow.

Fig. 20 is a sectional view taken along the line 19—20 of Fig. 18, viewed in the direction of the lower arrow.

Fig. 21 is a fragmental sectional detail view of a modified form of guiding and spacing block 50 in a guiding channel of the cage and having (in cross section) one of the rigid struts in position to be lowered into the seat therefor in the block.

The similar reference-numerals in these drawings correspond to similar parts in all the different views and in the following details of description; it being understood that herein, the word "rear" refers to the loading and discharging end of the cage and to the position of the respective elements in the cage.

The simplest form of this invention here shown in Fig. 1 is not the simplest-possible form that is useful; for certain parts can be eliminated without annulling its usefulness, as will be shown or implied hereinafter. Fig. 1 shows two explosion devices 1 each having spaced anchoring elements 2 to which two long flexible connectors 3 are secured either permanently or detachably, and such arrangement provides a large opening or enclosed space capable of receiving therein an upright or upstanding element of any target such as a ship or train; so this ammunition unit clings to the ship or train, even when moving along at a considerable speed, thereby cooperating with a time-controlled element of the explosion devices 70 for assuring contiguity of the ammunition-unit

to its target at the time of explosion of the explosion-devices so clinging to its target. However the effectiveness and sureness of this simplest form can be enhanced by certain additions and modifications, as follows:

To provide for properly launching this ammunition structure from an airplane so it will fall onto and become clinging attached to a target, it must be made collapsible and should be provided with guide-engaging elements for cooperation with guides in the launching device, also with means to retard or restrain movement of one of the explosion devices while the other one leaves the launching device and until the flexible connectors become fully extended and taut enough to pull the restrained explosion device from the launching device. Moreover the launched explosion devices should be substantially horizontal and evenly balanced so they remain horizontal or substantially so; for it is important that the enclosed space be in proper position to receive any upstanding object such as a mast, funnel, ventilating tube or davit on a ship that is the target; though such is not strictly essential, for where rigid struts are provided to assure that the flexible elements remain spaced from one another, and especially where the target is moving, an outstanding or forwardly projecting element of the target may be received between the flexible elements and between the explosion devices even when the latter are not horizontal. For the foregoing reasons, it is desirable (but not strictly essential) that the anchorages 2 be widely spaced on each explosion device, viz., on opposite end-portions, for instance, in peripheral outer flanges 4 of Fig. 1 and 4a of Figs. 5, 6, 8, 13, 14 and 15, and in these Figs. 5-15, the explosion devices are designated 1a.

The middle flange 4 (Fig. 1) of each explosion device is primarily to keep the coils or windings of cable separated from one another on the spool-like explosion device on which the cables or other flexible connectors are to be wound in collapsing the ammunition structure so the latter will be capable of occupying the comparatively small space in the launching device, as is shown in Fig. 2. It should be understood that each end of each explosion device, 1 and 1a, is provided with oppositely projecting track-engaging structures that include respectively a tubular bearing 5 and a bearing-block 6, the latter having a bore 7 (Figs. 13 and 14) that receives the tubular bearing 5 either tightly and non-rotatably, or with any desired degree of looseness and ease of rotation; or in lieu of the blocks 6 complementary blocks 6a, having complementary semi-cylindrical bearing-seats 1a (Figs. 15 and 17) may be used for sake of greater convenience in assembling while loading the ammunition-device into the launching device. However, while wooden blocks have thus far been contemplated and referred to, blocks 6/ and 6r of metal (Figs. 2, 2A, 2B) are preferable in some cases, especially where the front explosion device is rotatably supported on its tubular bearings 5 that serve as axles in the bearing-seats 7f (Fig. 2A), and where it is desired that said front explosion device be frictionally retarded or restrained, for in Figs. 2 and 2A it is seen that there is a surface-to-surface metal-to-metal contact of the block 6/ on the sub-jacent track on which it is seated to slide when forced to do so by weight and momentum of the rear explosion device and attached flexible connectors 3, 3a, 3b and/or 3c (Figs. 1, 2C, 2F, 3, 5, 6, 8, 10, 18); and here it should be understood that if the frictional re-

straint is found to be insufficient to keep the front explosion device in place while the flexible connectors are being unwound therefrom, viz., while the axles 5 are restrained against rotation by friction in the bearings 7, 7f or 1a, while the pull of the flexible connectors overcome such friction of the bearings; in such case any additional restraining device, as in Fig. 9A, can be used, the spring detent 8 being duplicated and applied to detents 9 on or in the respective guide-engaging blocks, instead of in the carriage 10 or 10a hereinafter described (Figs. 3, 4, 8, 11, 12).

Referring again to Figs. 2 and 2B, it is seen that the blocks 6r are of inverted-channel-beam structure and have wheels 11 journaled therein and normally seated on the rear end-portions of the track-elements 12 of the cage that comprises the main frame-work of this form of launching device and includes front uprights 13 that form abutments against which the front ends of the blocks 6r normally abut while their rear ends normally abut against the front ends of the blocks 6r whose rear ends normally abut against movable abutments 14; so it is seen that here is an interengagement of these abutments and blocks that normally prevents forward or rearward movement of these explosion devices in the cage, while the track-elements 12 and 12a prevent upward or downward or other movement thereof in case the airplane is turned over in manoeuvring while in battle. Here, it should be understood that all the elements mentioned in this paragraph are duplicated on the left side of the cage, which left side is omitted from this sectional view, and that the right and left sides are connected by cross-beams 15, and preferably connected by a floor 16 that has a down-curved rear end that cooperates with the open doors or abutments 14 to guide the ammunition device downward and rearward when being launched through the opening under the deflecting hood 17, this opening being normally closed by a yielding hinged section 18 or other appropriate form of closure of the fuselage floor to which the launching device is secured by the means shown or by any appropriate means. The foremost explosion device may have the major parts of the flexible connectors wound thereon either before or after being put into the cage of the launching device, for there are ample openings in the top of the cage for arms of the users to work through while their hands grasp and turn one or more of the peripheral flanges 4; but where the explosive devices are too heavy to be handled manually, any appropriate means may be provided for lifting them, one at a time, through the loading and launching opening under the hood 17, and other appropriate means may be provided for turning them so as to wind their respective portions of flexible connectors thereon.

For each abutment 14 there is a securing and releasing device that includes a rock-shaft 19 having a button 20 on its rear end and normally engaged with the abutment 14 so as to hold it against the rear end of the adjacent guide-engaging block. Each rock-shaft is journaled in the cage of the launching device and has a collar 21 that prevents forward movement of the rock-shaft and button and also serves as a hub for a handle-lever 22 having a link 23 pivoted thereto and provided with a pivot 24 that is connectable to a similar lever or arm (not shown) for effecting simultaneous operation of all the elements 19 and 20 so as to simultaneously release both abutments 14 by a single swing of either or both of the handle-

levers 22. If, when the abutments 14 are released, the airplane tips its front end upward or suddenly increases its speed while flying level, the wheeled blocks will roll off the guides or tracks 12 and gravitate to the yielding closure 18 which will thereby be forced open so the rearmost explosion device, by its weight and momentum, will pull the flexible connectors and cause them to unwind from the foremost explosion device before the latter starts toward the rear of the cage, because it is frictionally seated, as previously explained; but when the flexible connectors are fully extended and taut, they will pull the foremost explosion unit from the cage, and as it is then going at considerable velocity, it will be likely to strike the down-curved deflector 17 and thereby cooperate with gravitation for expediting its downward speed, so it will quite or nearly arrive at the same level as the first-launched explosion device and so the common plane of the flexible connectors and axes of the explosion devices will be in or approximately in horizontal relation when the ammunition device arrives at its target, and will accomplish its purpose as previously specified.

Referring now to Figures 3 to 21, and especially now to Figs. 3, 7 and 16, it will be seen that the launching device is relatively long and wide, its internal length several times its internal height or depth, and its internal width being at least twice its internal height or depth, such proportions being of importance for distributing the weight along and across the floor of the aircraft-fuselage, and especially where very long and heavy explosion devices are to be carried therein. Moreover, where the explosion devices are very heavy and long, it may not be very practical to wind the very long and heavy flexible connectors thereon and thus increase their respective weights; also, for increasing the factor of safety in carrying very heavy explosive devices and their guiding adjuncts, it is desirable to provide carriages, one for each explosion device, seated on the floor 16a of the cage, as best shown at 10 in Fig. 4 and 10a in Fig. 8; but not depending entirely on the floor and carriages for holding the explosion devices against untimely and detrimental movements, their relatively narrow intermediate peripheral rims or flanges 4a have their upper portions in and adapted to slide along inverted channel-beams 26 of the cage when being launched, but secured thereby against movement laterally of said channel beams. Moreover, the carriages are each provided with chock-blocks 10aa spaced from one another to receive and normally contain the lower parts of said intermediate flanges between them; whereby apparently sufficient safeguards are provided. However, additional safeguards are provided as follows:

Each carriage is provided with guide engaging elements 10b or 10ab (Figs. 4, 8 and 11) that are slidably seated for launching movement in front-to-rear direction along guiding tracks 12a (Figs. 3, 4, 7, 8, 9, 10, 16). A pair of guide-tracks 25 are secured, as parts of the cage, above the parallel to the guide-tracks 12a which are also integral parts of the cage; and it may be well to state here that all parts of the cage may be secured together by welding, riveting or other appropriate means, and that the hood 17 may be considered a permanent or removable adjunct of the cage. The tubular end projections 5 (Figs. 5, 8, 13, 14, 15) and their attached or adjoining guide-blocks 6, together with the several outwardly converging arms 1aa of the respective ends of the explosion

devices, constitute the guide-engaging projections or extensions of the explosion devices that engage with the guide-tracks 25 (or 25a in Fig. 4) and are slidable therealong when launching the ammunition device. Therefore, it is seen that all the elements 12a, 16a and 25 or 25a mutually contribute to the support and guidance of the explosion devices and their opposite end extensions or projections; also, that the channel-beams 26 cooperate in the guiding and in the supporting when the airplane is banking.

In addition to the mutual cooperations described in the foregoing, the following cooperation of the elements 1aa, 5, 6 and 25 is best understood in connection with Fig. 14 which shows only one of the two such structural combinations for each one of the explosion devices; for here it is seen that a practical and convenient means is provided to effect operation of one of the explosion producing devices 27 (see also Fig. 8). These explosion producing devices are essentially time-controlled and may be of any appropriate type or types, for instance, such as has attached thereto a restraining element 28 normally snugly but removably fitted in an opening of the explosion producer in proper relation to prevent operation of a clock-works that automatically begins to operate on removal of the restrainer 28, or is set in operation by such removal, and which causes the explosion in a predetermined time after its release from the restrainer; or removal of the restrainer may expose the chemical contents of the explosion producer to the entrance and action of water, so when one of these ammunition devices lies across a ship and has one or both of its explosion devices trailing in the water, a soluble or porous plug in the explosion producer acts as a time-controlled means to admit an effective amount of water within a few seconds, allowing the necessary time for the explosion device to move against the ship's hull or bottom where its explosion will produce the most destructive effect on the ship. To prevent untimely removal or displacement of the restrainer 28, two of the arms or struts 1aa are apertured to receive a tapered key 29 against the outer end of the restrainer 28, and such key should not be removed until the ammunition device is secured in the cage, for a reason now to be made apparent.

For removing the restrainer 28, a power-applying means is provided, viz., a grapple 30 that may well be of the construction shown in Fig. 14, being a plunger having a head 30a at its outer end and having spring-fingers 30b formed with notched inner ends and adapted to be forced over a conical outer end or head of the restrainer 28 for latching engagement with the latter. A helical compression spring 31 has one end seated on a shoulder or seat at the inner end of the tubular element 5 and has its outer end seated and compressed against the head 30a so it is adapted to automatically push the grapple outward to an extended position where it is arrested by its shoulders 30c abutting against the inner side of the bearing 1c, viz., the position shown in Figs. 5 and 6. In assembling, prior to loading in the launcher, the elements 28 and 29 are first placed in their normal position, as in Fig. 14; next, the spring is put in the tubular element 5; and next, the inner end of the grapple is put through the tubular element, spring and bearing 1c; then pressed inward against resistance of the spring 31 until its notched spring-fingers 30b snap into latching engagement with the conical head of

the restrainer 28; and now, it will be seen that this latching engagement combines with the key 29 to prevent untimely outward movement of the grapple and restrainer. Moreover, the grapple-fingers 30b are formed for frictional engagement with the tapered surface of the conical head, so the restrainer cannot be jarred or jolted from its normal position when the key 29 is removed; but of course, the heads 30a of each grapple must be against the vertical surfaces of the respective guide-tracks before the keys 29 are removed; and the keys must be replaced prior to removing the explosion-devices, except when such removal is intended to set the time-controlled explosion producers 27 in operation. However, when these explosion-devices are launched at a target, the heads 30a pass out of control of the guide-tracks 25, the spring 31 instantly cooperates with the grapple for pulling the restrainers, and all the exploders are immediately released for operation to cause explosions at predetermined intervals or environments.

Now assuming that the guiding and spacing blocks 6 are used (instead of the blocks 6a), and referring again to Fig. 3, it will be seen that the blocks 6 of the front explosion-device 1a are against the front end of the cage, and that the rear explosion-device 1a has its blocks 6 against the buttoned abutments whose construction and function are very similar to those of the previously described abutments 14 in Fig. 2. However, instead of these blocks 6 being abutted against one another, they are quite a distance apart, and the space between them in the respective guide-tracks 25 is filled with a series of disconnected or disunited blocks 6x that are held against displacement by flanges 25f (see Figs. 7, 8 and 9); and it is here stated that such blocks 6x and the carriages are launched separately from the explosion-devices, though at approximately the same instant, and that each falling block and carriage (even if made of wood) is heavy enough to inflict great damage on any person it may strike in falling from a considerable height. However, it may be preferable to eliminate the weight of these blocks 6x and apply that much additional weight of explosive material in the explosion-devices; and they may be substituted by keys 32 (Fig. 4) through bores in the guide-track and through a bore in each of the guide-blocks 25b, so the latter are secured in their respective normal positions without any need for the flanges 25f; but of course these keys 32 must be removed substantially an instant before the launching is to begin, or approximately when the movable abutments 14a are released or unbuttoned.

In the form shown in Figs. 5 and 6, chains 3b and 3c constitute the flexible connectors, though the cables of Fig. 1 or Fig. 2C could be substituted, or vice-versa; and inasmuch as the chain-sections 3b and 3c are united by links 3d or 3e (Figs. 5, 6, 10, 18 and 19), each unit 3b—3c—3d is one of the flexible connectors whose ends are either permanently or detachably connected to the explosion devices 1a. These flexible connectors are separated from one another as widely as is practical, consistent with convenience in loading them into the launching device and proper launching from the latter, for it is important that they fall on opposite sides of any upward projections (on the target) that be strong and securely anchored, for cooperation in attaching the ammunition device to the target, so the explosion or explosions will occur at one or both sides of the latter. To assure that the flexible

connectors remain widely spaced, at least one rigid strut 33 is provided, or substituted by the form of strut shown at 33a (Fig. 19), 33b (Figs. 2C-2E), or 33c (Figs. 2F, 2G); and preferably, a series of such struts, each having its end portions secured to the respective flexible connectors by any appropriate means, for instance, by the two-eye links 3d whose respective shanks are in radial bores through the struts, or by a spring-key 3f of U-shape (Figs. 18, 19) to lock the C-shaped link 3e against longitudinal movement through a slot in the strut, or by spot-welding as at 3ab (Figs. 2C, 2D, 2F) to prevent movement of the struts along the flexible connectors. The number of rigid struts and the predetermined distances between them may be varied according to requirements or desires of the mechanical designer.

When the ammunition-device of Fig. 5 is being placed in the launcher-cage, as in Figs. 3 and 8, the foremost explosive device may have one or more ropes etc, tied thereto and extended through the rear and front ends of the cage, so these ropes can be pulled by man-power or other appropriate means after the attached front explosion device is lifted into the opening under the hood or deflector 17 and has its guide-blocks seated on the lower elements of the guide-tracks 25 or 25a, and/or after this explosion-device is seated on its carriage 10 or 10a; and if the flexible connectors are then connected with the front explosion device, the pulling thereof must be gradual while the projected opposite ends of the struts are placed on or over the lower elements of the guide-tracks 12a and pushed forward. To properly space the struts from one another when the flexible connectors are collapsed, as shown in Fig. 6, blocks 34 (Figs. 5, 6, 2F and 2G), or 34a (Figs. 18, 20), or 34b (Fig. 21) are either permanently or detachably engaged with the respective end extensions of the rigid struts; and these guide-engaging elements have the three purposes of supporting, spacing and preventing the shifting of the struts and helping to prevent movement of the carriages from their normal positions, and the fourth purpose of co-acting with the guides 12a for properly guiding the struts rearwardly along and from the guide-tracks 12a in the launching operation. Blocks 34c (Fig. 6) are to be placed in the rear ends of the channel-tracks 12a for abutting against the movable abutments 14b (Figs. 3, 10, 16) and against the guiding and spacing elements 10b (Fig. 4) or 10ab (Figs. 10, 11). Here it is noted that the carriage 10a has end-extensions 10ac fitted into bores 10ad (Figs. 10, 11) of the blocks 10ab, whereas, the integral end-extensions 10b (Fig. 4) may be used instead of the blocks 10ab, either of these devices being a guide-engaging structure or element.

Again referring to the loading operation of the ammunition device into the launcher shown in Fig. 3; each carriage must first be placed on the rear end-portion of the floor 16a; and in order that the respective explosion-devices can each be then placed on its carriage before its track-engaging extensions are moved forward onto the tracks 25, it is necessary that the floor and the tracks 12a shall extend further to the rear than the tracks 25; and with respect to the rearmost carriage which is essentially under its burden that is normally between the rear ends of the shorter tracks and spaced from the rear ends of the longer tracks, the advantages of the space-filling blocks may be readily seen, viz., blocks 34c.

Now, having explained how the explosion-de-

VICES, their carriages and the struts are prevented from shifting in the cage, it will be explained how the flexible connectors are flexed, secured in their flexed positions (Fig. 6) and released from their securing means at the same instant the movable abutments are released from their securing means or buttons, as follows:

In Fig. 6, it is seen that each of the flexible connectors 3b has its outer bend or loop at 3d where secured to the respective struts, and has its inner bend adjacent to the median line of the assembly; so, when such assembly is in the launching cage (Figs. 3, 7, 9, 10), such inner bends 3i lie on the floor 16a, across the respective slots 16b where they are properly positioned to be engaged by hooks 35 (Figs. 3, 9, 10) that are secured on rock-shafts 36 and 37. These rock-shafts are journaled in appropriate bearing-elements 38, 39 and 40 (Figs. 4, 8, 9, 10) and are interconnected by spur-gears 41 and 42 interengaged and mounted respectively on the rock-shafts. A lever 43 is secured on the front end of rock-shaft 36, and adapted to be manually operated, viz., its upper end moved first from between two studs or stops 44, thence through about 90 degrees to the stud or stop 45, and such movement causes the hooks 35 to move outward and downward to positions below the floor from their normal effective positions shown where they engage with the inner bends of the flexible connectors 3b and are secured in such engagement by cooperation of the lever 43 and its keeper or studs 44; but when said hooks are moved out of engagement with each flexible connector, it is free to straighten out as the launching proceeds. A stud-handle 43a is preferably provided on the lever 43 to reduce the swing of the operator's hand and to expedite the operation of unhooking the flexible connectors and in unlatching or unbuttoning the abutments 14a and 14b; for the lever 43, in cooperation with the elements 36, 37, 41, 42 and other elements (presently described), releases the abutments 14a and 14b simultaneously with the release of the flexible connectors, as follows:

Arms 46 and 47 are secured respectively on the rock-shafts 36 and 37 and pivotally connected to links 48 which are pivotally connected to bell-cranks 49 and 50 that are journaled in bearings 51 on brackets 52 which are united with and project laterally from the floor 16a. Suitable upper and lower bearings 53 (Figs. 3) are provided on opposite sides of the cage, where holes for bolts or rivets are shown at 54 (Fig. 7), and four restraining elements 55 are journaled in the respective bearings. Each of these restraining elements includes a latch or button 56 and an arm 57. Two links 58 are provided on opposite sides of the cage, each of these links is pivotally connected to an arm of one of the bell-cranks 50 and to two arms 57 thereabove. Though only one of the movable abutments 14a is shown in Fig. 9, and only one abutment 14b is shown in Fig. 10, it is to be understood that there is one abutment 14a and one abutment 14b hinged in each pair of hinge-elements 14c, and that each latch or button 56 is normally engaged with one of such movable abutments; such normal position being shown in Figs. 3, 9 and 10, and out of the normal position in Fig. 16; this latter view also showing the abutments 14a and 14b in their out-of-the-way positions, so the launching can take place.

Referring again to Fig. 4, it is seen that two buttons or latches 59 are secured on the respective rock-shafts 36 and 37 and are normally

erect and against the rear side of the carriage 10, the front side of the carriage being against cage-posts 13a; but when the rock-shafts 36 and 37 are rotated for releasing the abutments 14a and 14b, they simultaneously turn the buttons or abutments 59 to positions below the floor 16a and thereby release the rear carriage at same time the front carriage, front explosion-device and flexible connectors are released; and all such releasing is effected by a single swing of the lever 43 from studs 44 to stud 45; but all parts of the ammunition device do not begin to launch simultaneously, because of the retarding or restraining means applied to the front carriage; so, when released, the rear carriage and its superposed explosion-device first pass out rearward from under the hood 17, and its weight and the force of air against it causes it to quickly stretch or straighten the flexible connectors, and when straightened, the latter will pull the front carriage rearward and out from the launching device, so the fully extended ammunition device will descend in an approximately horizontal position toward its target.

As a supplement to the abutments 59, or in lieu thereof, other forms of abutments may be provided, for instance, the keys 32 (Fig. 4), and it is quite within the scope of this invention to connect them to the lever 43 or to parts operated by the latter, so these keys will be removed when the other abutments are removed from their normal positions.

The several modifications of this invention, as here shown, do not exhaust the inventive ideas that could be illustrated and described; but they are evidence that numerous changes can be made within the scope of the inventive ideas as implied and claimed.

I claim the following as my invention:

1. A unitary ammunition structure that is adapted to be carried by and launched from a launching device and includes at least two widely spaced explosion devices each having anchorages that are spaced a considerable distance from one another, at least two long flexible connectors between said explosion devices and substantially parallel to one another, one of said flexible connectors having its opposite end-portions normally secured to an anchorage of each of said explosion-devices, a second one of said flexible connectors having its opposite end portions normally secured to two of said anchorages other than the anchorages to which the first said one of the flexible connectors is secured, and at least one rigid strut between and spaced from said explosion devices and having its opposite end-portions respectively secured to intermediate parts of said flexible connectors.

2. The structure defined by claim 1, and a series of rigid struts having end-portions secured to said flexible connectors and disposed at right-angles to the latter and in spaced parallel relation to the first said strut, the distance between adjacent struts being substantially the same as the distance between the flexible connectors, whereby, a series of substantially rectangular openings are provided between the explosion-devices, for a purpose specified.

3. The structure defined by claim 1, and the opposite end-portions of said rigid strut being extended slightly outward from said flexible connectors in a proper relation to engage with supporting elements in said launching device.

4. The structure defined by claim 1, and the opposite end portions of said rigid strut being

extended outward from said flexible connectors, and at least one bearing-block on each end-extension of the rigid strut in a proper relation to rest on and slide along supporting elements of said launching device.

5. The unitary structure defined by claim 1, in combination with a launching device which constitutes a cage in which said unitary structure is normally contained in a predetermined collapsed form, said cage being provided with securing means to normally engage with front and rear and intermediate parts of said unitary structure and to secure said parts of said unitary structure in said predetermined collapsed form in said cage, and in substantially fixed relation to one another, and means operable to release said unitary structure from said securing means and permitting said unitary structure to be launched from said cage.

6. The unitary structure defined by claim 1, in combination with a launching device that constitutes a cage in which each of said flexible connections is normally bent inward to approximately parallel relation to said rigid strut and secured by detaining means united with said cage, and operable for releasing them and other parts of the unitary structure, the foremost one of said explosion devices being provided with means to detain it in said cage while the rearmost one of said explosion devices leaves the cage and proceeds to expand the collapsed flexible connectors sufficiently to cooperate with the guide-engaging structures for releasing the detained explosion device from its detaining means, for purposes specified.

7. The unitary structure defined by claim 1, in combination with a launching device that includes a cage in which said unitary structure is normally disposed in collapsed form and is secured therein by means operable for releasing it, at least one of said explosion devices being provided with oppositely projecting guide-engaging structures, said cage having opposite sides provided with parallel guides that are normally substantially horizontal and have guide-engaging structures normally secured therein by means operable to release the latter and thus release said unitary structure at will of the user, at least one of said guide-engaging structures being provided with an automatic power-applying device normally in contact with one of said guides and thereby detained against operation and which is releasable for beginning operation when this explosion-device leaves the cage, this explosion device being provided with a time-controlled explosion producer and with means to detain the explosion producer against operation, the last said means being normally engaged with said power-applying device for cooperation in releasing the time-controlled explosion producer so as to permit the latter to operate after leaving said cage.

8. The unitary structure defined by claim 1, at least one of said explosion devices being spool-like and having at least a part of each of said flexible connectors wound thereon and adapted to be unwound therefrom, this one of the explosion devices being provided with a time-controlled explosion producer and a detaining means for the latter and having oppositely extending guide-engaging structures which include journals and include bearings for the journals, at least one of said journals being tubular, an automatic power-applying device in the tubular journal and normally engaged with said detaining means and

operable to actuate said detaining means so as to effect timely operation of said time-controlled explosion producer, and a cage having guides on which said guide-engaging structures are normally seated and adapted for movement therewith along for passing out of said cage, said automatic power-applying device being normally in contact with an element of said cage in a proper relation to be detained against operation and thereafter to be permitted to automatically operate when it passes out of contact with said cage.

9. A launching device for containing and launching a number of long explosion devices that are substantially mutually parallel and each in a substantially horizontal position, a substantially horizontally disposed cage whose inside width and length are each at least twice its inside height or depth and which can receive at least two of said long explosion devices, when the latter are disposed with their length across said inside width, substantially as shown, this launching device being provided with supporting and guiding means united with and extending along the right and left sides of the cage and adapted to cooperatively engage with opposite ends of the respective explosion devices so as to support and prevent detrimental movement of the explosion devices within the cage and to facilitate proper and timely launching of the explosion devices from the cage, this launching device being provided with restraining means properly located for engaging with each of the explosion devices to prevent untimely movement of each of the explosion devices in or from said launching device, said restraining means being operable for rendering it non-restraining so the respective explosion devices can be launched from the cage in a substantially horizontal position across the line of travel of an aircraft that carries said cage and its contents, this launching device being provided with connector-engaging means that include two parallel series of connector-engaging hooks, two interconnected rock-shafts on which the two series of hooks are respectively mounted in a proper relation to be swung toward and from the front-to-rear median plane of the cage, and actuating means on one of said rock-shafts and operable for cooperation in swinging the hooks to proper positions for engagement and disengagement with flexible connectors of the explosion devices when such connectors are engaged with the explosion devices in the cage and are looped in the manner described and shown.

10. In a launching device for carrying and launching a unitary structure that includes at least two explosion devices united by at least two flexible connectors, a cage having an apertured floor adapted to support said flexible connectors thereon when each of the latter is arranged in a series of bends that have portions adjacent to the respective apertures of said floor and when said explosion devices are respectively seated in front and rear end-portions of said cage, said cage being provided with restraining means to prevent detrimental and untimely movement of said explosion devices from their respective front and rear positions in said cage, said restraining means including a movable abutment at the rear end-portion of said cage, connector-engaging means movably mounted adjacent to the respective apertures of said floor and operable to be moved through said apertures and to engage with said bent portions of said connectors, and means operable for moving said

abutment and said connector-engaging means to proper positions for permitting said unitary structure to pass from said cage.

11. In combination with a launching device that includes a cage having opposite sides provided with parallel guides that are substantially horizontal, guide-engaging structures normally secured in engagement with said guides by means operable to release the guide-engaging structures, a unitary ammunition structure that includes explosion devices that are connected by long substantially parallel flexible connectors and have opposite ends engaged with and adapted to be guided by said guide-engaging structures along said guides when released for loading and launching the unitary ammunition structures, at least one of said explosion devices having one of its ends tubular and provided with an automatic power-applying device extending therethru and normally in contact with one of said guides and thereby restrained against operation and which is releasable for beginning operation when this explosion-device leaves the cage when launching it, this explosion device being provided with a time-controlled explosion producer and with means to detain the explosion producer against operation, the last-said means being normally engaged with said power-applying device for cooperation in releasing control of the time-controlled explosion producer so as to permit the latter to operate after it is launched from said cage.

12. In combination with a launching device that includes substantially horizontal parallel guides, guide-engaging structures normally engaged with said guides and releasable therefrom and adapted to slide therealong to be launched therefrom, an explosion device that has opposite axles normally engaged with said guide-engaging structures and has one of said axles tubular and provided with a power-applying device extending therethru and normally against one of said guides and thereby restrained against operation, said explosion device being provided with a time-controlled explosion producer and with means to detain the explosion-producer against operation, the last said means being normally engaged with said power-applying device for cooperation in releasing control of the explosion producer so as to permit the latter to operate after it is launched from the launching device.

13. A unitary ammunition structure that includes explosion devices secured to one another by substantially parallel flexible connectors which are spaced a considerable distance from one another, at least one of these explosion devices being spool-like and having an annular flange around its middle part and adapted to have at least a

portion of each of the flexible connectors wound therearound respectively at opposite sides of said annular flange so as to collapse or shorten this ammunition structure so as to adapt it to be received into a relatively short launching cage, this spool-like explosion device being provided with oppositely extending journals on which it is adapted to be supported by supporting and guiding or launching tracks of the launching cage and on which it is adapted to be rotated for being unwound for expanding the collapsed ammunition structure.

14. The ammunition structure defined by claim 13, in combination with a launching cage that includes launching tracks on which the said oppositely extending journals are supported and adapted to be moved to the launching position, at least one of said journals being tubular and having a power-applying device extending substantially therethru and normally against one of said launching tracks by which it is detained against operation, this spool-like explosion-device being provided with a time-controlled explosion producer and with detaining means for the latter, said power-applying device being normally engaged with said detaining means and adapted to render the latter ineffective when the power-applying device is moved out of contact with the launching track in the operation of launching the ammunition structure from the launching track.
